UNITED STATES PATENT OFFICE.

GEORGE LOWDEN, OF BROOKLYN, NEW YORK.

VELOCIPED.

SPECIFICATION forming part of Letters Patent No. 247,078, dated September 13, 1881.

Application filed April 6, 1881. (No model.)

To all whom it may concern:

Be it known that I, GEORGE LOWDEN, a citizen of the United States, residing at Brooklyn, in the county of Kings and State of New York, have invented new and useful Improvements in Velocipedes, of which the following is a specification.

This invention relates to that class of velocipedes for which Letters Patent of the United States were granted to me October 26, 1880, No. 233,682; and it consists in a certain novel arrangement of the driving mechanism; also, in a peculiar arrangement of the forward or steering axle; further, in a brake of certain novel construction, as hereinafter more fully set forth.

This invention is illustrated in the accompanying drawings, in which Figure 1 represents a vertical longitudinal section. Fig. 2 is an inverted plan view; Figs. 3 and 4, detail views of the pawl-arms.

Similar letters indicate corresponding parts.

The letters A B designate the axles, supporting a body, C, and D D' E E' the wheels, two on each axle.

To the rear axle, A, is fixed a ratchet-wheel, F, and on opposite sides of this wheel are located arms G, swinging loosely on the axles, and each carrying a pawl, H, adapted to engage the ratchet-wheel.

The letter I designates a frame arranged to oscillate on pivots *a* upon the body C, and carrying handles *b* at its ends, this frame being yoke-shaped.

J designates compound levers, connected to the pawl-arms G at one end and to the handle-frame I at the other end; K, toggle-levers, connected to the rear axle, A, at one end and to the handle-frame at the other end, and L links connecting the compound levers to the toggle-levers. When an oscillating motion is imparted to the handle-frame I the toggle-levers K are alternately spread apart and drawn together, and these levers act on the pawl-arms G through the compound levers J and links L to oscillate the same, moving the pawl-arms in opposite directions, whereby the pawls are caused to engage the ratchet-wheel and a continuous forward motion is given thereto.

The pawls H are weighted at their inner ends to remain in gear with the ratchet-wheel

F, and the pawl-arms G are provided with stops *s*, which are arranged to come in contact with each other in the motions of the arms, thus regulating such motions.

55

It will be perceived that the driving mechanism above described differs from that described in my before-mentioned patent, in that the toggle-levers K are connected to the axle A instead of an independent shaft, while the motion of the levers is produced by the handle-frame I in lieu of the saddle.

If desired, the driving mechanism can be utilized for giving motion to a sewing-machine or the like, as by elevating the body C from the ground, removing one of the rear wheels, D, and substituting therefor a pulley to be connected with the part to be driven.

The forward axle, B, is yoke-shaped, and is secured to a central steering-post, N, which passes up through the body C and carries pedals at its upper end, as at *d*. On opposite sides of this post N are located springs O, which are connected to the body C at one end and to the axle B at the other end, so that by 75 the joint action of these springs the axle is kept in a transverse or normal position. In other words, when the axle B is turned for steering the vehicle and released it is returned to a transverse position, thus bringing the forward wheels into line with the rear wheels. The arrangement of these springs O is capable of various modifications, which will readily suggest themselves to a skilled mechanic.

The letter P indicates an elbow-lever, which 85 is pivoted to the body C at such a point that the arm *e* of this lever is opposite to the rear wheel, D, and may be brought into contact with this wheel, thus acting as a brake. For the purpose of throwing said arm *e* of the elbow-lever into contact with the wheel D, I connect to its other arm, *f*, a reciprocating rod, Q, which is guided vertically in the body C and provided with a suitable handle at its upper end.

What I claim as new, and desire to secure 95 by Letters Patent, is—

1. The combination, substantially as hereinbefore set forth, of the rear or driving axle, the ratchet-wheel fixed to the rear axle, the pawl-arms mounted loosely on the rear axle, the oscillating handle-frame, the compound levers, connected to the pawl-arms at one end and to

100

the handle-frame at the other end, and the links connecting the compound levers to the toggle-levers, for the purpose set forth.

2. The yoke-shaped front axle, B, having attached to its central portion the vertical steering-post N, which projects through the vehicle-body and has its upper end provided with pedals d, in combination with two springs, O, connected at their rear ends directly with the bottom of the vehicle-body and at their forward ends directly to the yoked axle on opposite sides of the steering-post, substantially as described.

3. The elbow-lever P, pivoted at its angle to the vehicle-body C, and having a lateral brake-arm, e, and arm f, in combination with the vertically-guided rod Q, connected with the arm f of the elbow-lever, substantially as described. 15

In testimony whereof I have hereunto set my hand and seal in the presence of two subscribing witnesses.

GEORGE LOWDEN. [L. S.]
